UNITED STATES PATENT OFFICE.

HERBERT C. SEGELKEN, OF PHOENICIA, NEW YORK.

SPOUT.

Application filed April 16, 1928. Serial No. 270,322.

The present invention relates to a spout which is designed to be used on containers for facilitating the pouring of the contents of the container into another container. More 5 specifically the invention relates to a spout which may be used on glass jars and the like containing oil so that the oil may be readily poured into the crank case of an internal combustion engine.

10 Of course the invention is in no way limited to this particular use which is mentioned by way of example.

An important object of the invention resides in the provision of a spout of this nature 15 which when the container is in an upright position will function as a closure for the container to protect the contents thereof from the element and which may be controlled when the container is tilted so as to allow the 20 contents to flow freely therefrom and to be stopped whenever desired.

A still further very important object of the invention resides in the provision of a spout of this nature which is exceedingly simple in its construction, inexpensive to manufacture, strong and durable, convenient to operate, and thoroughly efficient and reliable 25 in use.

With the above and numerous other objects 30 in view as will appear as the description proceeds, the invention resides in certain novel features of construction, and in the combination and arrangement of parts as will be hereinafter more fully described and claimed.

35 In the drawing:

Figure 1 is a side elevation of the spout showing the same in an upright closed position,

40 Figure 2 is a side elevation of the spout showing the same in an inclined open position,

Figure 3 is a longitudinal section through the spout,

45 Figures 4, 5 and 6 are detail sections taken substantially and respectively on the lines 4—4, 5—5 and 6—6 of Figure 3, and

Figure 7 is a perspective view of the inner sleeve and cap.

50 Referring to the embodiment of the invention illustrated in the drawing it will be seen that the numeral 5 denotes the glass jar with a neck threadedly receiving a cap like member 6 from which obliquely extends a spout sleeve 7 in which is telescopically

mounted a sleeve 8 limited in its movement in the sleeve 7 by a pin and slot connection. 55

The slot is indicated by the numeral 9 and the pin is in the form of a lug 10 depressed inwardly from the sleeve 7 to extend into the slot 9 thus permitting the sleeve 8 to slide longitudinally in the sleeve 7 but preventing the rotation of the sleeve 8 in the sleeve 7. On the outer end of the sleeve 8 there is fixed or formed integrally a cap like disk 11 to close the outer end of the sleeve 7 when the sleeve 8 is contracted therein. 60

65 The outer end of the sleeve 8 is provided with an elongated outlet opening 12 diametrically opposed to the slot 9. An ear 14 projects outwardly from the lower portion of the sleeve 7 and has slidably therethrough a rod 15 connected to the disk 11.

The lower end of the rod 15 is offset laterally at 16 to provide a finger grip. From the above detailed description it will be seen that when the spout structure is disposed as 75 shown in Figure 1 the said spout is closed by the disk 11 so as to protect the contents of the container 5 from the elements.

By tilting the container 5 the spout may be placed in the position shown in Figure 80 2 at which time the inner sleeve 8 may be telescoped outwardly to its extended position which is permitted by the pin and slot connection described and therefore the contents of the container may flow through the sleeve 85 and out through the elongated opening 12 and the effective length of this opening may be adjusted by sliding the sleeve 8 in respect to the sleeve 7 until the opening is completely closed as will be quite apparent. 90

This sliding of the sleeve 8 in respect to the sleeve 7 is conveniently attained by means of the rod 15 and the finger grip 16 as will be quite apparent.

95 It is thought that the construction, operation and utility and advantages of this invention will now be quite apparent to those skilled in this art without a more detailed description thereof. The present embodiment of the invention has been disclosed in 100 considerable detail merely for the purposes of exemplification since in actual practice it attains the features of advantage enumerated as desirable in the statement of the invention and the above description. It will be apparent that changes in the details of con- 105

struction, and in the combination and arrangement of parts may be resorted to without departing from the spirit or scope of the invention as hereinafter claimed or sacrificing any of its advantages.

Having thus described my invention, what I claim as new is:

In a spout structure of the class described, an outer sleeve, an inner sleeve slideable in the outer sleeve, a pin and slot connection between the sleeves permitting the inner sleeve to slide in the outer sleeve but pre-

venting it from rotating therein, said inner sleeve having at its outer end an elongated opening, a disk over the outer end of 15 the inner sleeve and extending beyond said inner sleeve to close against the outer end of the outer sleeve, means for sliding the inner sleeve in the outer sleeve, said means comprising an apertured ear projecting outwardly from the outer sleeve, a rod slideable therethrough and connected with the disk.

In testimony whereof I affix my signature.
HERBERT C. SEGELKEN.
